UNITED STATES PATENT OFFICE

142,798

DESIGN FOR A COMBINED SERVING TRAY, RECEPTACLE, AND GAME DEVICE

Eldridge B. Taylor, Cleveland, Ohio

Application March 9, 1945, Serial No. 118,378

Term of patent 14 years

(Cl. D44—10)

To all whom it may concern:

Be it known that I, Eldridge B. Taylor, a citizen of the United States, residing at Cleveland, in the county of Cuyahoga and State of Ohio, have invented a new, original, and ornamental Design for a Combined Serving Tray, Receptacle, and Game Device, of which the following is a specification, reference being had to the accompanying drawing, forming a part thereof, wherein:

bined serving tray, receptacle, and game device showing my new design, the side opposite that illustrated being substantially like that shown including a continuation of the horse picture portion of the device.

I claim:

The ornamental design for a combined serving tray, receptacle, and game device, substantially as shown and described.

ELDRIDGE B. TAYLOR.
